UNITED STATES PATENT OFFICE.

EDWIN B. PROUDFIT, OF WESTFIELD, NEW JERSEY, ASSIGNOR TO THE AEOLIAN COMPANY, A CORPORATION OF CONNECTICUT.

NOTE-SHEET FOR AUTOMATIC MUSICAL INSTRUMENTS.

1,218,698.

Specification of Letters Patent.

Patented Mar. 13, 1917.

Application filed February 18, 1910, Serial No. 544,593. Renewed December 15, 1916. Serial No. 137,251.

To all whom it may concern:

Be it known that I, EDWIN B. PROUDFIT, a citizen of the United States, and resident of the town of Westfield, county of Union, 5 and State of New Jersey, have invented certain new and useful Improvements in Note-Sheets for Automatic Musical Instruments, of which the following is a specification.

My invention relates generally to certain 10 new and useful improvements in perforated note sheets for self-playing or automatically operated musical instruments, and more particularly to a novel system of marking the sheets to indicate to the performer 15 groups of notes, each of which is to be differentiated from the adjoining groups, in such manner as the player prefers, to express his conception of the proper interpretation of the composition. The marks which 20 I employ are of different values and constitute what I shall term phrasing indications or punctuation marks.

The perforated note sheets now so largely used, and of which I have knowledge, are 25 marked with a waving or irregular longitudinal line indicating where the notes should be loud or soft, such line being termed the "expression line." They are also marked with a line indicating the speed 30 at which the note sheet should travel, said line being known under various names, such as the "tempo line" or "metrostyle line." There are many variations in the methods 35 of marking a roll or music sheet for "expression" as it is termed, meaning the volume of sound, or the intensity of the sound, and the "tempo," meaning the speed of the music sheet. These markings are not to be confused with my markings as the purpose 40 thereof differs completely from the purpose of my markings.

In order to make clear the purpose of my invention, I shall liken expression in music to expression in literature. It is quite accurate, and will serve to aid in defining my invention, to state that music is a succession 45 of clearly defined phrases of various lengths linked together to form sentences, and these sentences in turn combined to complete paragraphs. Thus, expression in music means, in its broader sense, first the proper punctuation or division of the music into phrases,

sentences and paragraphs, and then emphasizing or laying stress on the important parts of such phrases, sentences and paragraphs in such manner as appeals to the taste of the performer.

The difficulty in giving proper expression to music lies in knowing where to place the punctuation; how to tell where the phrases, 60 sentences and paragraphs begin and end. Where they begin and where they end is not a matter of personal opinion of the performer. They cannot be changed by the performer any more than the punctuation 65 marks in literature may be disregarded. The important points or climaxes are also fixed and unchangeable, but in the amount of emphasis, stress or accent, the degree of difference between the important and unimportant part, lies one of the great points of 70 personal interpretation.

To properly play a musical composition by means of an automatic musical instrument, such as a player-piano operated pneumatically or otherwise by means of a perforated note sheet, the notes must be properly punctuated or grouped, and each group given the intended emphasis.

The perforated music sheets in use today 80 fail utterly to indicate to the performer the punctuation of the musical composition and do not indicate in the slightest degree the beginning or the end of any group of notes requiring emphasis or separation from the 85 adjoining groups. The result is that the ordinary performer without a musical education and training will drive a music sheet through the automatic playing instrument giving the variations in volume of sound indicated by the expression line, but will not group the notes or accentuate or emphasize any part of said groups. He will not know 90 that he is rendering a composition made up of phrases, sentences and paragraphs which 95 are as clearly defined and should be as rigidly observed as similar divisions in literature.

It is the main object of this invention to provide, in a perforated music sheet, phrasing or punctuation marks of different values, 100 which shall indicate to the performer the division of the notes into groups corresponding to phrases, sentences and paragraphs of literature.

Another object of this invention is to provide certain markings between the phrasing indications, or punctuation marks, indicating the amount of emphasis to be given the 5 notes between said punctuation marks.

It will thus be seen that I not only group the notes and separate the groups by indications or marks of different values, but that I also indicate the emphasis to be given 10 to each group of notes, the emphasis indications being arranged between the phrasing indications or punctuation marks and preferably consisting of a continuous marking 15 extending longitudinally of the sheet from one punctuation mark to the next.

In the drawing the single figure indicates a portion of a perforated music sheet provided with my punctuation and emphasis indications.

20 Referring to the various parts by numerals, 1 designates the note sheet and 2 the perforations therein, by means of which the notes are sounded. On this sheet I provide a series of phrasing or punctuation indications 25 3, 4 and 5. These marks are of different values and indicate that different degrees of retard, accent, change of tone or other musical effect should be employed to give to each mark its proper value. The 30 mark 3 is of the least value and indicates that a slight change in musical effect is to mark the notes separated by such indication, said change in effect preferably to be given at the point marked when said point 35 reaches the tracker bar of the instrument. This division corresponds in value to a phrase in literature, and said marking may be likened to a comma as it has substantially the same function and performs substantially 40 the same office as a comma in English composition. The mark 4 is of higher value and corresponds to the period of literature and indicates the end of a sentence or a group of notes of which all 45 the preceding phrases form a part. This mark indicates that a more pronounced musical effect should be employed to separate the group of notes marked by it from the adjoining group. This musical effect may 50 be produced by a retard, accent, change of tone, hold or dwell, or other means, as may be desired by the performer. The mark 5 is of still higher value and designates the end of what may be termed a paragraph in the 55 musical composition. This mark indicates that the theme or melody is complete, and marks the end of a group of notes of which all the preceding phrases, and sentences form a part. The group of notes of 60 which this mark defines the end should be distinctly separated from the next preceding group by a more marked musical effect than that employed at the preceding mark 4. The performer will at once understand that the

end of this group of notes is to be as clearly 65 defined in the performance of the musical composition as the corresponding division is defined in literature.

It is to be understood that these punctuation marks or phrasing indications are to 70 be continued throughout the entire note sheet, and that said marks will be repeated throughout each paragraph of the composition. The marks indicating the end of a paragraph divide the note perforations into 75 main groups, and these main groups are in turn divided into intermediate subordinate groups by the marks of lesser value. The marks, therefore, bear a distinct and well-defined relation to each other. The marks 5 80 may be termed the main marks which divide the note perforations transversely of the sheet into main groups, and the marks 4 are intermediate subordinate marks which divide the main groups of note perforations into subord- 85 inate groups, and the marks 3 may be termed secondary subordinate marks which divide the subordinate groups, each of said groups of note perforations bearing a distinct and well-defined relation to each other. 90

Between the phrasing indications or punctuations, I place what I term emphasis indications by which I define the amount of emphasis to be given the notes in the group. These indications are continuous from one 95 phrasing mark to the next, and indicate how the emphasis is to be applied during the playing of the entire group of notes. In the drawing I have shown the emphasis indications as two lines, 6, running longitudinally 100 of the note sheet, said lines diverging to indicate an increasing emphasis, and converging to indicate a decreasing emphasis. These markings taken in connection with the phrasing indications or punctuations, will 105 enable a player to group the notes; to give the proper emphasis to each group, and to separate the groups according to the phrasing indications.

In the music rolls or note sheets as 110 they have been heretofore marked, the ordinary player follows the marks on the roll without any thought of personal expression or interpretation. With rolls or note sheets marked according to my invention, a player 115 will be informed of the beginning and end of each group of notes, and of the relative values of the musical effects, such as retard, accent, change of tone, hold or dwell, which is to mark the separation of the groups. 120 However, whether the notes in each group, or at the end thereof shall be played softly or not is a matter entirely within the control of the operator and is to be governed by his taste. For instance, he may end a para- 125 graph softly if he desires, or with a great volume of sound, to suit his understanding or interpretation of the musical composition.

He should, however, observe in some manner the punctuation marks or phrasing indications which separate the groups. The player will also be informed by the emphasis marks 5 of how the notes in each group should be emphasized, these emphasis marks being arranged between the punctuation or phrasing marks, and relating to the notes between said marks.

10 The value of my two sets of markings is manifest. By means of them I point out clearly and simply the fundamentals of musical expression, namely the division of the composition into groups of notes corresponding 15 to phrases, sentences and paragraphs in literature, and indicating the emphasis to be given to the notes of each group.

It will, of course, be understood that the phrasing indications or punctuation marks 20 may be in any form desired, those shown on the drawing being used merely by way of illustration, and I wish it understood that I am not to be limited to any particular form of mark.

25 It is also to be understood that the emphasis indications between the phrasing indications may be marked in any suitable manner, and I do not wish to be limited to the precise form of marking shown.

30 As shown in the drawing, some of the marks intersect note perforations and some of them do not, but this is quite immaterial as the placing of the marks will depend upon the character of the musical composition.

35 Having thus fully described my invention, what I claim as new and desire to secure by Letters Patent is:

1. A perforated note sheet provided with main marks dividing the note perforations 40 transversely of the sheet into main groups, said main marks indicating the ends of the themes forming the musical composition and with intermediate subordinate marks dividing the main groups of note perforations 45 transversely of the sheet into subordinate groups, said marks differing in appearance

from the main marks and indicating the subordinate divisions of the musical composition which make up the themes.

2. A perforated note sheet provided with 50 main marks dividing the note perforations transversely of the sheet into main groups, said main marks indicating the ends of themes forming the musical composition, and with intermediate subordinate marks 55 dividing the main groups of note perforations transversely of the sheet into subordinate groups, said marks indicating the subordinate divisions of the musical composition which make up the themes. 60

3. A perforated music sheet provided throughout its length with marks dividing the note perforations transversely of the sheet into main groups and indicating some change in the operation of the musical instrument, and subordinate marks dividing the note sheet transversely into subordinate groups, and indicating some change in the operation of the musical instrument, the change indicated by the main group marks 70 being more pronounced than that indicated by the subordinate group marks.

4. A perforated note sheet provided with main marks dividing the note perforations transversely of the sheet into main groups, 75 said main marks indicating the ends of themes forming the musical composition, and with intermediate subordinate marks dividing the main groups of note perforations transversely of the sheet into subordinate 80 groups, and indicating the subordinate divisions of the musical composition which make up the themes, and emphasis marks extending longitudinally of the sheet and extending between said group marks. 85

In testimony whereof I hereunto affix my signature in the presence of two witnesses this 17th day of February, 1910.

EDWIN B. PROUDFIT.
